UNITED STATES PATENT OFFICE.

WILLIAM JACKSON SCHOONOVER, OF BELVIDERE, ILLINOIS.

GEARING FOR WASHING-MACHINES.

1,274,087.

Specification of Letters Patent. Patented July 30, 1918.

Application filed June 28, 1916. Serial No. 106,308.

To all whom it may concern:

Be it known that I, WILLIAM J. SCHOONOVER, a citizen of the United States, and a resident of Belvidere, in the county of Boone 5 and State of Illinois, have invented certain new and useful Improvements in Gearing for Washing-Machines, of which the following is a full, clear, and exact specification.

10 My invention is concerned with gearing for washing machines, and is designed to produce a gearing of the class described that shall be suitable primarily for hand-operated lever washing machines of the vacuum 15 or pounder type, in which the operating mechanism extends upward through the bottom of the tub.

To illustrate my invention, I annex hereto three sheets of drawings, in which the same 20 reference characters are used to designate identical parts in all the figures, of which—

Figure 1 is a vertical section as seen substantially on the line 1—1 of Fig. 2;

Fig. 2 is a plan view in section as seen on 25 the line 2—2 of Fig. 1;

Fig. 3 is a view in section on a larger scale on the line 3—3 of Fig. 1;

Fig. 4 is a detail in section, as seen on the line 4—4 of Fig. 3;

30 Fig. 5 is a view in section as seen on the line 5—5 of Fig. 1, with the parts on the scale shown in Figs. 3 and 4;

Fig. 6, sheet 2, is an enlarged view of the upper end of the vertically reciprocating 35 rod carrying the cups, but with the parts in position as they would be seen from the left-hand side of Fig. 1; and

Fig. 7 is a view in section on the line 7—7 of Fig. 6.

40 In carrying out my invention, I preferably apply it to the ordinary tub 10 having the cover 11, the bottom 12, and supported by the legs 13. Pivoted on the side of the tub, as by the bracket 14, is a hand lever 15, which preferably has the detachable handle 16 supported when in use in the socket 17, forming the upper end of the metallic portion of the hand lever 15. Pivoted on the lower end of the hand lever 15, is the pitman 18, the other end of which is pivoted on the outer end of the stud 19, eccentrically mounted in the spur gear wheel 20, which is journaled on the stud shaft 21 supported from the bracket 22 secured to the under side of the bottom 12 of the tub, and preferably having the foot

portion 23, which is supported on the wooden bar 24 extending transversely beneath the center of the bottom of the tub, and supported by the angle bars 25 connecting the legs 13. To equalize the operation of the machine and cause it to operate easily once it is started, I journal on the bearing stud 26 supported in the outer end of the arm 27 projecting downward and outward from the bracket 22, the heavy fly-wheel 28, which has the rather long hub 29 terminating in the spur gear pinion 30 meshing with the spur gear wheel 20, so that as the hand lever is operated, the fly-wheel 28 is speeded up in 70 the customary manner.

Journalled on the pin 19, between the pitman 18 and the spur gear wheel 20, is a rectangular bearing block 31, which is adapted to slide back and forth in the horizontal bearing aperture 32, of the head 33, which is pinned or otherwise rigidly secured on the lower end of the vertical reciprocating rod 34, which, as best seen in Fig. 5, is adapted to slide up and down in the bearing sleeve 35, the main portion of which extends upward into the center of the tub above the normal water line, while the somewhat reduced and threaded lower portion 36 extends through the bottom 12 of the tub and the arm 37 of the bracket 22, and has the stuffing nut 38 screwed on its lower end to hold the sleeve in position and form a water-tight packing for the rod 34. I may employ in connection with the head 33, the guiding bar 39, pinned in the under side thereof and extending down through an aperture formed in the foot 23 of the bracket 22, and also through the registering aperture in the wooden bar 24. The sleeve 35 preferably has the horizontal flange 40 which rests on the packing disk 41 interposed between the flange and the bottom 12 of the tub, as best seen in Fig. 5.

On the upper end of the rod 34, I mount 100 the hub 42 of the spider 43, which preferably has the three arms diverging at equal angles, and supporting the cups 44 on the under sides of their outer ends, so that as the rod 34 reciprocates, the cups will be moved down 105 to the dotted-line position shown in Fig. 1, and back to the full-line position. The spider is mounted to turn freely upon the reduced upper end of the shaft 34, and for this purpose I pass the pin 45 into the hub 42 and into the semi-circular annular groove 46 formed in the reduced upper end of the

rod 34, so that the spider will be free to rotate on the shaft 34 while it must rise and fall with it. To rotate the spider a short distance on the rod 34 at each reciprocation thereof, I preferably employ the mechanism best illustrated in Figs. 6 and 7, where it will be seen that I secure a collar 47 on the rod 34 a suitable distance beneath the hub 42, which has the ratchet teeth 48 formed on its under side. On a flattened cut-away face 49 of the collar 47, I fulcrum the short lever 50, as by the screw 51. On one end of said lever, as by the screw 52, I fulcrum the dog 53, the lower end of which is enlarged or weighted so that the dog tends to stand in a vertical position with its nose 54 engaging the ratchet teeth 48. A pin 55, projecting from the corresponding end of the lever 50, serves to limit the movement of the dog 53 in one direction. To the other end of the lever 50, I pivotally connect the rod or link 56, which extends downward through an aperture in a flange or collar 57, extending horizontally from the top of the guiding sleeve 35. An enlargement 58 on the bottom of the rod 56 beneath the flange 57 limits the extent of the upward movement of the rod, with the result that during practically all of the reciprocating movement of the rod 35, except the last portion of its upward movement, the weight of the dog 53 over-balances the weight of the rod 56, and the parts stand in their relative position, shown in Fig. 6. Near the limit of the upward movement of the rod 34, the head 58 contacts with the under side of the flange 57, and stops the further upward movement of the rod 56, with the result that the lever 50 is swung on its fulcrum 51, and the nose 54 of the dog 53 is swung a short distance through the arc of a circle sufficient to advance the hub 42 of the spider through the angular distance represented by one or two of the ratchet teeth 48. To protect the rod 56 from possible contact with the clothes which fill the lower part of the tub about the sleeve 35, I preferably provide in connection with said sleeve the elongated pocket 59, which may be cast integral with and form a part of said sleeve.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

What I claim as new, and desire to secure by Letters Patent of the United States is:

1. In a gearing, the combination with a support adapted to hold water and having a vertical bearing sleeve extending through the central portion of the bottom thereof, of a shaft mounted to reciprocate lengthwise

in said bearing, a horizontally-slotted cross-head secured on the lower end of the shaft, a gear wheel journaled beneath said support adjacent the cross head, an eccentric pin thereon extending into and coöperating with the cross head to reciprocate the shaft, a fly-wheel journaled beneath the support, a gear pinion connected to the hub of the fly-wheel and meshing with the gear wheel, and means for rotating said gear wheel. 75

2. In a gearing, the combination with a support adapted to hold water and having a vertical bearing sleeve extending through the central portion of the bottom thereof, of a shaft mounted to reciprocate lengthwise in said bearing, a horizontally-slotted cross-head secured on the lower end of the shaft, a gear wheel journaled beneath said support adjacent the cross-head, an eccentric pin thereon extending into and coöperating with the cross-head to reciprocate the shaft, a fly-wheel journaled beneath the support, a gear pinion connected to the hub of the fly-wheel and meshing with the gear wheel, a swinging lever fulcrumed on the side of the support, and a pitman connecting the load end of the lever and the eccentric pin. 80 85 90

3. In a gearing, the combination with a support adapted to hold water and having a vertical bearing sleeve extending through the central portion of the bottom thereof, of a shaft mounted to reciprocate lengthwise in said bearing, means located beneath the support and connected to the lower end of the shaft to reciprocate it lengthwise, a spider mounted to rotate on the upper end of the shaft, and connections between the spider and the shaft actuated by the movement of the latter to rotate the spider step by step. 95 100 105

4. In a gearing, the combination with a support adapted to hold water and having a vertical bearing sleeve extending through the central portion of the bottom thereof, of a shaft mounted to reciprocate lengthwise in said bearing, means connected to the lower end of the shaft to reciprocate it lengthwise, a spider mounted to rotate on the upper end of the shaft, a ratchet mounted on the spider, a dog coöperating with the ratchet, and other connections between the spider and the shaft actuated by the movement of the latter to reciprocate the dog to rotate the spider. 110 115 120

5. In a gearing, the combination with a support having a vertical bearing-sleeve extending therethrough, of a shaft mounted to reciprocate lengthwise in said bearing, means connected at one end of the shaft to reciprocate it lengthwise, a spider mounted to rotate on the other end of the shaft, and connections between the spider and the shaft actuated by the movement of the latter to rotate the spider step by step. 125 130

6. In a gearing, the combination with a support adapted to hold water and having a vertical bearing sleeve extending therethrough, of a shaft mounted to reciprocate lengthwise in said bearing, a swinging lever fulcrumed upon the side of the support, a pitman connected to the load end of the lever, a gear wheel carrying an eccentric pin to which the other end of the pitman is connected, said gear wheel being located beneath the support, connections between the eccentric pin and the shaft for reciprocating the latter lengthwise, a fly-wheel also journaled beneath the support, a pinion on the hub of the fly-wheel meshing with the gear wheel, a spider mounted to rotate on the upper end of the shaft, and connections between the spider and shaft actuated by the movement of the latter to rotate the spider step by step.

7. In a gearing, the combination with a support having a vertical bearing-sleeve extending therethrough, of a shaft mounted to reciprocate lengthwise in said bearing, a swinging lever fulcrumed on the support, a pitman connected to the load end of the lever, a gear wheel carrying an eccentric pin to which the other end of the pitman is connected, connections between the eccentric pin and the shaft for reciprocating it lengthwise, a fly-wheel, a pinion on the hub of the fly-wheel meshing with the gear wheel, a spider mounted to rotate on the other end of the shaft, and connections between the spider and shaft actuated by the movement of the latter to rotate the spider step by step.

8. In a gearing, the combination with a support having a vertical bearing-sleeve extending therethrough, of a shaft mounted to reciprocate lengthwise in said bearing, means connected at one end of the shaft to reciprocate it lengthwise, a spider mounted to rotate on the other end of the shaft, a ratchet mounted on the spider, a dog coöperating with the ratchet, and other connections between the spider and the shaft actuated by the movement of the latter to reciprocate the dog to rotate the spider.

9. In a gearing, the combination with a support having a vertical bearing-sleeve extending therethrough, of a shaft mounted to reciprocate lengthwise in said bearing, means connected at one end of the shaft to reciprocate it lengthwise, a spider mounted to rotate on the other end of the shaft, a ratchet mounted on the spider, a dog coöper-

ating with the ratchet, a rod depending alongside the shaft and connected with the dog, and connections between the rod and the vertical bearing-sleeve to move the rod to swing the dog.

10. In a gearing, the combination with a support having a vertical bearing-sleeve extending therethrough, of a shaft mounted to reciprocate lengthwise in said bearing, means connected with one end of the shaft to reciprocate it lengthwise, a spider mounted to rotate on the other end of the shaft, a ratchet mounted on the spider, a lever fulcrumed on the upper end of the shaft, a dog pivoted on one end of the lever, a rod depending alongside the shaft from the other end of the lever, and means to stop the longitudinal movement of the rod to cause the dog to rotate the spider at the end of the upward movement of the shaft.

11. In a gearing, the combination with a support having a vertical bearing-sleeve extending therethrough, of a shaft mounted to reciprocate lengthwise in said bearing, means connected with one end of the shaft to reciprocate it lengthwise, a spider mounted to rotate on the other end of the shaft, a ratchet mounted on the spider, a lever fulcrumed on the upper end of the shaft, a dog pivoted on one end of the lever, a rod depending alongside the shaft from the other end of the lever, said sleeve having an elongated pocket therein to receive the rod, and connections between the rod and pocket to move the rod to actuate the dog.

12. In a gearing, the combination with a support having a vertical bearing-sleeve extending therethrough, of a shaft mounted to reciprocate lengthwise in said bearing, a horizontally slotted cross-head secured on one end of the shaft, a bracket depending from the support, a horizontal bearing-shaft projecting from the bracket, a gear wheel journaled on the horizontal shaft, an eccentric pin thereon extending into the slotted cross-head, an arm extending from the bracket, a second horizontal bearing-shaft for the fly-wheel projecting from said arm, a fly-wheel on said second bearing-shaft, a pinion on the hub of the fly-wheel meshing with the gear wheel, and means for rotating the gear wheel, all of the foregoing elements being directly beneath the support.

In witness whereof I have hereunto set my hand and affixed my seal, this 21st day of June, A. D. 1916.

WILLIAM JACKSON SCHOONOVER. [L. S.]
